UNITED STATES PATENT OFFICE.

JOHN F. THIESSEN, OF LOS ANGELES, CALIFORNIA.

DESIGN FOR A COMBINED ASH TRAY AND BUTT EXTINGUISHER.

Application filed September 27, 1927. Serial No. 23,560. Term of patent 7 years.

To all whom it may concern:

Be it known that I, JOHN F. THIESSEN, a citizen of the United States, residing at Los Angeles, in the county of Los Angeles and State of California, have invented a Combined Ash Tray and Butt Extinguisher, of which the following is a specification, reference being had to the accompanying drawing, forming a part thereof.

The figures are respectively a perspective view and top plan view of an ash tray and butt extinguisher, showing my new design.

I claim:

The ornamental design for a combined ash tray and butt extinguisher as shown.

JOHN F. THIESSEN.
